(57) **CLAIM**

The ornamental design for a pump for liquids, as shown and described.

DESCRIPTION

Fig. 1.1: Axonometric view of the pump for liquids according to the claimed design;

Fig. 1.2: Front view thereof;

Fig. 1.3: Left view thereof;

Fig. 1.4: Back view thereof;

Fig. 1.5: Right view thereof;

Fig. 1.6: Top view thereof; and

Fig. 1.7: Bottom view thereof.

The portions of the article shown in broken lines form no part of the claimed design.

1 Claim, 7 Drawing Sheets
